United States Patent Office.

GOTTFRIED AUGUST H. HERTZER, OF WATERFORD, MICHIGAN.

Letters Patent No. 95,227, dated September 28, 1869.

IMPROVED RAILWAY-RAIL CHAIR.

The Schedule referred to in these Letters Patent and making part of the same.

To whom it may concern:

Be it known that I, GOTTFRIED AUGUST H. HERTZER, of Waterford, in the county of Oakland, and State of Michigan, have invented a new and useful Improvement in Rail-Joints; and I do declare that the following is a true and accurate description thereof, reference being had to the accompanying drawings, and to the letters of reference marked thereon, and being a part of this specification, in which—

Figure 1 is a plan view of my improved joint; Figure 2 is a cross-section of the same, on the line $x-x$ in fig. 1; and

Figures 3 and 4 are plan views of the under sides of the lock-plates.

Like letters refer to like parts in each figure.

The nature of this invention relates to an improvement in the construction of joints for railway-bars, and consists in a peculiar arrangement of bolts in a chair, and in the employment of peculiar cups recessed to receive the nuts of said bolts, for preventing their turning and loosening from the vibration of passing trains.

In the drawings—

A represents a cross-tie, on which is secured the chair B, by spikes b.

This chair is formed with a cheek-piece, B', which projects under the head, against the web of the rail C, on its outer side.

Projecting through from the inner side of the rail, through the cheek-piece B', are two or more fish-bolts, D.

On their threaded ends are nuts d, which draw the rail to the cheek-piece of the chair.

E is a slotted stud, projecting from the cheek-piece between the fish-bolts.

F is a lock-plate, having an opening by which it is slipped over the stud E.

On its under side are two rectangular recesses, f, corresponding in size and position to the nuts d, so that when the plate is placed in position, these nuts will enter the recesses and be prevented from turning.

The plates are held in place by a key of sheet-metal, e, pressed through the slot in the stud and bent, to prevent withdrawal.

On the inner side of the rail, two bolts, G, and a stud, H, project upward from the chair, each bolt being provided with a nut, g.

I is a clamp, which lies on the chair, so formed as to embrace the lower part of the web of the rail and its foot.

It is also provided with proper openings, to allow it to be slipped to its seat on the bolts and studs, where it is secured by the nuts g.

J is a lock-plate, similar in construction to that already described, and is secured in place by a key, j, passing through a slot in the stud H.

The tie A is sunk the thickness of the chair B, below the plane of the other ties.

It will clearly be seen that, with a joint thus arranged, the lamination of the ends of the rails is entirely obviated, and that its efficiency is not liable to be impaired by reason of the loosening of the nuts, which is prevented by the employment of the lock-plates.

As the chair, clamp, and lock-plates may be constructed of cast-iron, the cost of the joint will be comparatively small.

What I claim as my invention, and desire to secure by Letters Patent, is—

The chair B B', provided with the stud E, in combination with the clamp I, provided with the stud H, and with the bolts D and G, provided with nuts d and g, and with the lock-plates F and J, and keys e and j, when the several parts are constructed and arranged to operate as and for the purposes above set forth.

GOTTFRIED AUGUST H. HERTZER.
